UNITED STATES PATENT OFFICE.

GEORGE F. DE WEIN, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

VANNER.

1,081,894.

Specification of Letters Patent.

Patented Dec. 16, 1913.

Application filed May 3, 1909. Serial No. 493,647.

To all whom it may concern:

Be it known that I, GEORGE F. DE WEIN, a citizen of the United States, residing at Milwaukee, in the county of Milwaukee and 5 State of Wisconsin, have invented a certain new and useful Improvement in Vanners, of which the following is a specification.

This invention relates to improvements in the construction of vanners and in particular 10 to the vanner hanger saddles as combined with the vanner frame.

The object of the invention is to provide simple hanger saddles for the vanner frame which will allow the frame to be inclined 15 toward either end, this inclination depending upon the class of material under treatment, without cramping the frame supporting means providing for lateral reciproca-

20 A clear conception of the invention can be obtained by referring to the accompanying drawing in which like reference characters designate the same parts in different views.

25 Figure 1 is an end view of a hanger saddle built according to the invention and shows its attachment to a side beam of the frame, shown in section. Fig. 2 is a front view of same, the clamping bolt being shown 30 in section. Fig. 3 is a side view of a vanner frame in a horizontal position, showing the relative positions of two of the saddles attached to the frame. Fig. 4 is a similar view showing the frame inclined toward 35 one end.

The vanner hanger saddle consists essentially of a flat oval shaped plate 3 having a projection 7 at its lower end which extends in a direction at right angles to the plate 3 40 and has a curved upper surface. The top of the plate 3 is formed as an enlarged cylindrical portion 10 and a strengthening rib 9 is added. The cylindrical portion 10 has its axis parallel to the side beams 1, and has 45 a bore 8 passing axially therethrough. A plurality of contact lugs 6, preferably three, are formed on the flat side of the plate 3 facing the side beams 1 and on the same side, upon which the projection 7 is formed.

50 The clamping bolt 4 carrying the nut 14 passes through a circular hole in the frame beam 1 and through an opening 5 in the plate 3. Two of the saddles, one on each side of the frame, have elongated openings 55 5, while the openings 5 through the other

two saddles are circular, but allow some play for the bolts passing therethrough.

In suspending the vanner frame upon the saddles, the saddles are first attached to the transversely swinging suspending rods, not 60 shown, by means of pins passing through the openings 8. The frame beams 1 rest on the upper surfaces of the projections 7, see Figs. 3, 4.

If the frame is to be suspended horizontally, the beams 1 are clamped to the saddle plates 3 by means of the bolts 4 and nuts 14, as shown in Fig. 3. If the frame is to be inclined, either one of the saddles is moved up or down, thus giving inclination to the 70 frame, as shown in Fig. 4. During the shifting process it is necessary to release the nuts 14 so that the frame can swing to its required position and yet allow adjustment of the frame on the lugs 7 to any angular 75 position and for necessary separation of the saddles. The curvature of the upper surface of the projection 7 is such that as the beam swings about the bolts 4, its lower part will always coact upon the curved surface 80 of the projection 7. The play between the bolts 4 and the circular holes at the one end of the vanner will permit such coaction, but will not prevent cramping of the suspending means when the angular position of the 85 vanner is extreme. As it is desirous to keep the horizontal distance between the saddles constant to prevent cramping of the suspending means permitting lateral reciproca-

90 tion, and since the corresponding horizontal distance between the bolts 4 varies as the inclination of the beams 1 varies, the passages 5 for the bolts 4 in two of the saddles must be in the form of a slot, see Fig. 2.

95 It should be understood that it is not desired to be limited to the exact details of construction shown and described, for obvious modifications will occur to a person skilled in the art.

100 It is claimed and desired to secure by Letters Patent:

1. The combination of a frame of an element adapted to be laterally reciprocated and adjustably tilted from end to end, and at least two hanger saddles adapted in combination to be spaced apart a constant distance measured on a horizontal line, the frame adapted to be adjustably swung on the saddles and at least one of the saddles 105 adapted to be adjustably slid along the 110

frame longitudinally thereof and said saddles having horizontal bores for suspension of said frame to permit lateral vibration thereof, and clamping means for connecting the saddles to the frame when adjusted.

2. The combination of a frame of an element adapted to be laterally reciprocated and adjustably tilted from end to end, and at least two hanger saddles adapted in combination to be spaced apart a constant distance measured on a horizontal line, the frame adapted to be adjustably swung on the saddles and said saddles having horizontal bores for suspension of said frame to permit lateral vibration thereof, and a bolt connecting each saddle to the frame when adjusted, one of the connected parts having an elongated opening extending along the length of the frame and having one of said bolts passing therethrough.

3. The combination of a frame of an element adapted to be laterally reciprocated and adjustably tilted from end to end, and at least two hanger saddles adapted in combination to be spaced apart a constant distance measured on a horizontal line, the frame adapted to be adjustably swung on the saddles and said saddles having horizontal bores for suspension of said frame to permit lateral vibration thereof, and a bolt connecting each saddle to the frame when adjusted, at least one of said saddles having an extension in contact with said frame one of the parts at said contact being curved to permit rolling between the parts and one of said parts having an elongated opening extending generally in the same direction as the chord of said curved part, one of said bolts extending through said elongated opening.

4. The combination of a frame of an element adapted to be laterally reciprocated and adjustably tilted from end to end, and at least two hanger saddles adapted in combination to be spaced apart a constant distance measured on a horizontal line, the frame adapted to be adjustably swung on the saddles and said saddles having three lugs for lateral contact with said frame and said saddles having horizontal bores for suspension of said frame to permit lateral vibration thereof, and a bolt connecting each saddle to the frame when adjusted, at least one of said saddles having an extension with a curved upper surface under said frame for supporting same and having an elongated opening therein within the triangle formed by said lugs, one of said bolts extending through said elongated opening.

5. The combination of a frame of an element adapted to be laterally vibrated and longitudinally adjustably tilted, a hanger saddle having three lugs for lateral contact with said frame, said saddle having a horizontal bore for suspension of said frame to permit lateral vibration thereof, and a bolt connecting said saddle to said frame, said saddle having an extension with a curved upper surface under said frame for supporting same and for adjustably swinging said frame thereon and having an elongated opening therein within the triangle formed by said lugs, said bolt extending through said elongated opening.

In testimony whereof I affix my signature in the presence of two witnesses.

G. F. DE WEIN.
